UNITED STATES PATENT OFFICE.

ROBERT E. SHEAL, OF CLEVELAND, OHIO.

MATERIAL-HANDLING BRIDGE.

Application filed December 3, 1921. Serial No. 519,725.

To all whom it may concern:

Be it known that I, ROBERT E. SHEAL, a citizen of the United States, residing at Cleveland, in the county of Cuyahoga and 5 State of Ohio, have invented a certain new and useful Improvement in Material-Handling Bridges, of which the following is a full, clear, and exact description, reference being had to the accompanying drawings.

10 This invention relates to hoisting and conveying machinery of the traveling crane type and has to do with means for anchoring the traveling structure when in a stationary position. An example of such a structure is a 15 material-handling bridge, such for example as that described in my application for Letters Patent filed November 12, 1921, Serial No. 514,583, in which is set forth a traveling structure adapted to be propelled along its 20 tracks by means of a toothed device suitably secured to the traveling structure and cooperating with a rack located parallel to the tracks, or runway on which said structure travels, although it will be understood that 25 the device may be applied to any structure of this nature designed to move along a fixed path.

A traveling structure of this nature may 30 be of great size and considerable weight and consequently have such momentum that if it once becomes started by wind pressure on its immense superstructure or from any other cause, it is likely to disregard all anchoring provisions, even when moving at 35 low speed. My invention is not designed to stop the movement of the structure when in motion but has for its object the provision of means whereby the structure may be secured against becoming accidentally set in motion; secondary objects of the invention 40 are the provision of simple and substantial devices carried by the structure and adapted to engage some part of the runway in securing relation; the provision of means whereby 45 the said devices may be readily lowered into or raised from cooperative relation with said runway and means whereby such devices may be moved longitudinally of the runway so as to register with shouldered portions of 50 said runway in bracing relation; while further objects and advantages of the invention will become apparent as the description proceeds.

55 Specific means by which the above objects may be accomplished will be set forth in detail in the accompanying drawings; it being

understood that the forms here shown are intended to be merely illustrative and in no way limiting my invention to any of the specific structures here shown, except as recited 60 in the appended claims.

In the drawings; Fig. 1 illustrates a traveling bridge having one form of my invention attached at one end of its base; Fig. 2 is an enlarged detail view of a portion of the 65 same device showing the anchoring spud attached to the base of the bridge and in position to anchor the bridge on the track; Fig. 3 is a view similar to Fig. 2 and at right angles thereto; Fig. 4 is a detail sectional view 70 taken on line 4-4 of Fig. 3, and showing details of one of the toggle operating means; Fig. 5 illustrates another form of anchoring device; and Fig. 6 illustrates a modification 75 of said last form.

Referring to the drawings in detail by reference characters, 1 designates a foundation, and 2 a supporting track for the wheels 3, 3 of trucks 4, 4. Carried by these trucks is a base member or sill 5 from which rises the 80 tower 6 of the bridge; located between the tracks 2, is a rack comprising side bars 8, and cross pins 9 connecting the bars 8 at intervals and with which a pinion 7 on the bridge 85 coacts in propelling the bridge along its tracks.

Each anchoring device comprises an anchor member or spud suitably secured to the end of the base member or sill 5 and adapted to engage the rack or other suitable part of the runway such as the ties which support the tracks 2-2. In the embodiment shown in Figs. 1 to 4 inclusive, each spud comprises spaced side members 12 secured together by cross members 14, its lower end being provided with a head 17 having a plurality of teeth 19, adapted to engage the rack. The spuds are here shown as attached to the ends of arms 23 pivotally attached by one end to the sill as at 24 and by the other end to the 90 ends 25 of a trunnion 26 passing through holes in the side members 12, although any mode which allows vertical and pivotal movement can be employed.

Secured to the sill approximately above 105 the trunnion 26 are brackets 28 to which are pivoted the upper ends of links 30 whose lower ends are pivoted to the upper ends of links 31 whose lower ends in turn are pivoted to the trunnion 26 in such wise as 110 to produce toggle joints. In this embodiment I have shown two such toggles, one

at each side of the spud. The middle joint of each toggle comprises a pivot member 33 pierced by a transverse threaded hole receiving the screw 34. One end of this screw is journaled in a bracket 35 which in turn is pivoted to the sill 5 upon a horizontal axis which coincides with the shaft 36. Each screw 34 is provided with a bevel gear 37 meshing with a companion gear on the shaft 36, and this shaft is provided at one end with a sprocket 38.

Surrounding the upper end of the spud is a horizontal rigid bracket 40 which carries the slideable carriage 41, in which is journaled the cross bar 42. This cross bar is pierced and threaded for the screw 43, which is journaled in bearings 44, 44 at opposite ends of the bracket. The inner end of this screw is provided with a bevel gear 45 meshing with a companion gear 46 carried by the shaft 47, whose end is provided with the sprocket wheel 48. The upper end of the spud is slotted as shown at 50, 50 to permit the passage of the cross-bar 43 therethrough. Accordingly the spud is merely swung sideways by this cross bar, which has no supporting relation therewith; and the spud is raised and lowered by the toggle joint, which has no directive relation therewith.

Journaled to the sill at any convenient point are two sleeves 52, 53, the former within the latter. The inner sleeve 52, carries at its outer end the hand wheel 54 and at its inner end the sprocket wheel 55 which is connected by a chain 56 with the sprocket wheel 48. The outer sleeve 53 carries at its outer end the hand wheel 57 and at its inner end the sprocket wheel 58 connected by a chain 59 with the sprocket wheel 38.

Rotation of the large hand wheel 57 therefore serves to buckle or straighten the toggle joint, thus raising or lowering the spud, and rotation of the smaller hand wheel 50 swings the spud so that its teeth may register properly with the rack or with the ties of the supporting track. The dotted lines show the spud in an elevated and shifted position. It will be understood that the structure must be brought to rest before this device is brought into use and that the purpose of moving the spud laterally is only to cause its teeth to register with the cross pins of rack or ties. The toggle joint not only provides a device of great mechanical advantage for raising and lowering the spuds (one of which not infrequently weighs several tons) but also when straightened constitutes a lock to hold the anchor in engaging position. It will be understood, however, that other means may be employed for raising and lowering the spud and adjusting the same than those shown in the drawings.

65. Under certain circumstances the form of

anchoring device shown in Fig. 5 may be found desirable on account of its simplicity of construction and operation. This form of anchoring device comprises a spud shank 65 having a head 66 on its lower end 70 and having one or more teeth 67 on its lower surface adapted to cooperate with the rack pins, ties, or other cross members carried by the foundation. The spud is supported at the end of the sill by means of a pivot 68 carried by the cross head 69 slideable in the bracket 70 and moved by the screw 71. A counterweight 72 is secured to the upper end of the spud shank 65 to assist in raising the spud in disconnecting the same from the track. A chain 73 may be provided by which the shank 65 may be raised and lowered and held in elevated position, this chain or cable being manipulated by suitable means such as a windlass, (not shown). 85 The screw is shown as provided with a capstan head 74 adapted to receive iron bars in order to turn the same, although other means may be employed. An advantage of this form of spud, aside from its 90 simplicity of construction, is that the force tending to move the tower is exerted longitudinally, thereby decreasing the strain and allowing a lighter construction. A disadvantage is that it must be used in pairs 95 since it will stop movement only in one direction, while the first described device will work both ways and generally need not be duplicated. Another advantage of the second form is that the lateral spread 100 of the device may sometimes limit the travel of the bridge. With the construction shown in Figs. 1 to 4 the travel of the bridge is not limited and the spuds form bumpers, pads 11 being shown to receive the impact. 105

When used in pairs the spuds may be connected for simultaneous operation: also the handwheel or capstan head method here shown is only illustrative and any manual or power operated mechanism can be employed, controlled and operated either close at hand or from a distance; and while I have described these illustrative embodiments in detail I do not limit myself to any of such details except as recited in my annexed claims which I desire to have construed broadly.

Having thus described my invention what I claim is:

1. In combination, a material bridge moving along fixed tracks or runways, a rack, means on the structure cooperating with the rack for propelling the same along the tracks, an anchor secured to the structure and adapted to be brought into cooperating relation with said rack to hold the structure stationary on the track, and means for moving said anchor along the bridge parallel to the rack to cause it to engage tightly the teeth of the same.

2. In combination, a traveling structure adapted to move along fixed tracks or runways, a rack slidably mounted along said track or runway, and means on the structure cooperating with said rack for propelling the structure along said tracks or runways, an anchor carried by said structure and having teeth thereon adapted to be brought into cooperative relation with said rack to hold the structure in stationary position on its tracks, means for raising and lowering said anchor, and means for moving said anchor longitudinally a sufficient amount to cause its teeth to register with the rack teeth.
3. In combination, a traveling bridge, supporting and propelling means therefor comprising a longitudinal track or runway and spaced transverse members adjacent to said track or runway, a spud carried by said bridge and formed at its lower end to cooperate with said transverse members, means whereby said spud can be raised and lowered and means whereby its lower end can be moved along the track into engaging relation with such members.
4. In combination, a traveling bridge, a fixed track or runway therefor, cross members having a fixed position relatively to said track or runway, and an anchoring device carried by said bridge and adapted to engage said cross members, said device comprising a spud having one or more teeth at its lower end adapted to engage said cross members, a screw threaded member operable to align said teeth with said cross members, and means for raising and lowering said spud.
5. In combination, a traveling bridge, a track or runway for supporting the same, fixed transverse members located at spaced intervals along said track and means for anchoring said bridge, comprising a spud movably attached to said bridge, and a toggle for lowering said spud into and raising it out of cooperative relation with said members.
6. In a traveling bridge, a track or runway, cross members rigid relatively to the track, a spud carried by said bridge and having one end formed to engage said cross members, means for raising and lowering said spud, and means independent of said raising and lowering means for moving the engaging end of said spud longitudinally of said track to bring the same into engaging relation to said cross members.
7. In combination, a traveling bridge, a support therefor including tracks, and means for anchoring the bridge in stationary position comprising a spud, a portion of which is adapted to engage said support to hold the bridge stationary on its tracks, a horizontally movable carriage, a screw for moving said carriage, a toggle, one arm of which is secured to the spud and the other to the bridge, and screw threaded means for operating the toggle to raise and lower the spud, said spud having a vertical sliding engagement with said carriage.
8. In a traveling bridge, in combination, a supporting structure comprising a track and spaced cross members fixed relatively thereto, a spud having a portion adapted to engage said cross members, means for raising and lowering said spud, and independent means for adjusting said spud longitudinally.
9. In a device of the character described, the combination with a supporting runway having spaced transverse abutments, and a structure movable therewith, of an anchoring member pivotally connected to said structure and having one end shaped to engage the sides of said abutments, means for raising and lowering said member and means carried by said structure for moving said member longitudinally of said runway so as to bring it into registering relation with said abutments.
10. In a device of the character described, the combination with a supporting runway having spaced transverse oppositely facing abutments and a structure movable therewith, of an anchoring member carried by said structure in approximately upright position, the lower end of said member being shaped to fit between adjacent abutments, means for raising and lowering said member, and means for moving the lower end of said member longitudinally of said runway to bring it into register with the spaces between adjacent abutments.
11. The combination with a runway of a rack supported parallel thereto, a movable structure on said runway and movable parallel to said rack, an anchoring device carried by said structure and adapted to engage said rack, and means for adjusting said anchoring device along said structure to cause it to register with said rack.

In testimony whereof, I hereunto affix my signature.

ROBERT E. SHEAL.
